Claims priority, application Austria July 24, 1958
3 Claims. (Cl. 156—286)

This invention relates to an apparatus for producing ozone by a silent discharge of electricity between a plurality of flat, plate-shaped electrodes which are arranged in spaced juxtaposed relation, alternately connected to opposite poles of a source of high voltage and attached to dielectric plates which project roundabout over the edges of the electrodes.

Such so-called plate ozonizers are known per se and have, as compared with tube ozonizers in which the electrodes are formed by coaxial tubes disposed within each other, the advantage that they require less space for a given total electrode surface, thus rendering possible the manufacture of comparatively small apparatus.

A great problem in apparatus for producing ozone by a silent electric discharge is the corrosion of the electrodes, especially when the air to be ozonized is predried only partially or not at all. Although the yield of ozone with dried air is greater, for technical use apparatus are demanded whose efficiency is somewhat lower, but on the other hand do not require the costly additional appliances for drying the air and the attention on these appliances. Such ozonizers are particularly suitable for temporary operation in small waterworks, industrial concerns and for mobile plants, say, in the army. The ozone produced is mainly utilized for sterilizing water.

In order to avoid corrosion of the electrodes, corrosion- and glow-proof dielectrics have already been interposed between the electrodes and the discharge space, to thus keep away from the electrodes any aggressive substances in the discharge space. But also the air, possibly present between the dielectrics and the electrodes, may lead to corrosion of the electrodes, since a glow discharge occurs there also.

In order to avoid any corrosion of the electrodes, the invention contemplates embedding each electrode between two dielectric plates, and filling the space completely between these plates and between them and the embedded electrodes with an adhesive binder, to be thus free from air. In addition, through the adhesive binder the two dielectric plates and the intermediate electrodes are united to a coherent plate-shaped structural element.

The above and other advantageous features of the invention will hereinafter more fully appear from the description, the claims and the accompanying drawing, wherein there are shown purely by way of example one preferred embodiment and two modified forms of the object of invention.

In said annexed drawing:

FIG. 1 shows diagrammatically a sectional view of an apparatus with a plurality of plate-shaped electrodes, taken on the line I—I of FIG. 2;

FIG. 2 shows a section of the same apparatus, taken on the line II—II of FIG. 1;

FIG. 3 shows on a larger scale a structural element of the apparatus with a single electrode as viewed from left to right in FIGS. 1 and 2;

2

FIG. 4 is a cross-section taken on the line IV—IV of FIG. 3, on a larger scale;

FIG. 5 shows a fragmentary view of a modified form of the structural element in a representation similar to FIG. 3;

FIG. 6 is a cross-section taken on the line VI—VI of FIG. 5, on a larger scale;

FIG. 7 shows a fragmentary view of another modified form of the structural element, likewise in representation similar to FIG. 3.

The apparatus shown in FIGS. 1 and 2 comprises a casing 10 which preferably consists of some corrosion-proof synthetic material. Two walls 11 opposite each other of the casing 10 are broken through and joined with connecting parts 12, into each of which a pipe 13 opens respectively for supplying the air to be ozonized and for carrying off the air enriched with ozone.

The casing 10 has arranged in it a plurality of plate-shaped structural elements 15 in spaced juxtaposed relation. Although each of said elements 15 is composed of several parts which, however, constitute a coherent structural unit as explained further below, for the sake of clarity FIGS. 1 and 2 show each the elements 15 as a single part only. On their inner sides the casing walls 11 have grooves which are engaged by the elements 15, as clearly shown in FIG. 2. The elements 15 are retained in their proper position by the ribs formed between said grooves.

FIGS. 3 and 4 show one of the elements 15 on a larger scale. It comprises two plates 16 and 17 of dielectric material, preferably glass, having embedded therebetween a flat, plate-shaped electrode 18. The plates 16, 17 and the electrode 18 are connected to each other by an adhesive binder 19 which is also dielectric and completely fills the space between the plates 16, 17 and between them and the electrode 18 so that the space is free from air. Alternatively, instead of glass, the plates 16, 17 may consist of mica or ceramic material or some organic synthetic substance. In the form, according to FIGS. 3 and 4, the electrode 18 is a metal foil, especially of aluminum. The electrode 18 has formed on it an integral connecting lug 20 which projects beyond the edge of the plates 16, 17 and has a slit 21. The two dielectric plates 16, 17 are larger than the electrode 18, and the plates 16, 17 project roundabout at least 10 mm. beyond the edges of the electrode 18, preferably 20–30 mm., depending on the voltage of the source of high potential used for producing the ozone. As an adhesive binder 19, a polymer synthetic substance, especially polyvinyl acetate, is suitable. As will be seen in FIG. 3, the metal foil electrode is visible through one sheet of glass and one layer of binder, both of which are transparent.

The described elements 15 which among each other are all of identical design, are so positioned in the casing 10 that the connecting lugs 20 of the successive elements 15 alternately project upwards and downwards, as shown in FIG. 1. All upwardly projecting lugs 20 are clamped between metallic spacer sleeves 22 through which a threaded bar 23 is passed. Said bar is supported in the walls of the casing 10 and secured by means of nuts 24. An additional nut 25 serves for clamping the spacer sleeves 22 together with the lugs 20 engaging therein. In an entirely similar way, the downwardly projecting connecting lugs 20 of the elements 15 are clamped between metallic spacer sleeves 26, through which passes a threaded bar 27 which is supported in the casing 10 and

secured by means of nuts 28. An additional nut 29 on the bar 27 serves for clamping the spacer sleeves 26 together with the connecting lugs 20 engaging therebetween.

The metallic threaded bars 23, 27 are connected to one end or the other of the secondary winding of a high-voltage transformer 30 serving as a source of high voltage. In this way, the electrodes 18 arranged in spaced juxtaposition are alternately connected to opposite poles of the source of high voltage 30.

The action of the described apparatus is as follows:

The air to be ozonized is blown into the casing 10 through one of the pipes 13, and then passed through the interspaces between the elements 15, where a silent electric discharge, a so-called glow-discharge, takes place, whereby ozone is formed. The A.C. voltage applied to the electrodes 18 amounts to between 6,000 and 20,000 volts. The ozone enriched with air is permitted to escape at the other side of the casing 10 through the pipe 13 connected there. The dielectric plates 16, 17 and the binder 19 of each structural element 15 prevent the substances present within the discharge space from reaching the electrodes 18 so as to protect them from corrosion, which otherwise would occur owing to the generated aggressive gases, such as ozone, various oxides of nitrogen and nitric acid. Consequently, the described apparatus is also suitable for operation with air that is not or only incompletely predried. Furthermore, the binder 19 and the plates 16, 17 will prevent the metal of the electrodes 18 from being atomized through the glow-discharges on the surface thereof, whereby also the formation of electrically conductive layers of precipitate upon the dielectric plates 16, 17 will be prevented. Only the component parts located in the glow-zone, i.e. adjacent the discharge space are known to be endangered by corrosion, for which reason the connecting lugs 20, spacer sleeves 22, 26, threaded bars 23, 27 and nuts 25, 29 located substantially outside the discharge space will be much less subject to corrosion.

It is of advantage to have the dielectric plates 16, 17 of each element 15 made of an inorganic material, inasmuch as, for instance, organic synthetic substances, are indeed corrosion-proof, but less capable of withstanding the stresses caused by the electric glow-discharge. The binder 19 of the elements 15 may, however, without disadvantage, be an organic synthetic substance, as it will be protected by the dielectric plates 16, 17 against the harmful influences of the glow-discharge.

The structural element 15 may, for instance, be manufactured as follows:

On a support (not shown) a glass plate 16 is first laid which, depending on its size, may be 1-5 mm. thick. Then said plate 16 is covered with a foil 0.25-1 mm. thick, which mainly consists of polyvinyl acetate and includes softeners, such as tricresyl phosphate. Subsequently, on said foil the metal electrode 18 is laid, which may be, for instance, 0.1-0.3 mm. thick. Following this, a second foil of polyvinyl acetate is laid over the electrode 18, and thereupon the whole is covered with a second glass plate 17. By evacuation, any air possibly present between said parts is drawn off, whereupon the composite body is heated in an autoclave and pressed together by means of a pressure gas. While being heated, the polyvinyl acetate foils become plastic and intimately bound to the plates 16, 17 and electrode 18. Thereby the portions of the synthetic foils immediately overlying each other outside the edges of the electrode weld together. Finally, the composite body is allowed to cool, and the synthetic substance, which possibly has come out between the plates 16, 17, is cut off. The electrode 18, plates 16, 17 and the synthetic substance 19 serving as an adhesive binder, now constitute the cohering, practically inseparable structural element 15 which can be conveniently built into the casing 10.

In FIGS. 5 and 6 there is shown a modified form of a structural element 115. It is distinguished from the

described elements 15 in that the electrode 118 is not a metal foil, but a covering, say, a metallic layer or a non-metallic electrically conducting layer, applied to one dielectric plate. The layer 118 may be applied in a manner known per se, by spraying-on, depositing by vaporization, depositing from a solution, etc., whereby the layer may be given any desired shape by making use of suitable templates or the like. In the manufacture of the element 115, only a single plastic foil of, say, polyvinyl acetate, may be placed between the plate 17 provided with the layer, and the other plate 16, whereafter the procedure is the same as described with reference to the structural element 15. After heating and pressing, the plastic foil forms an adhesive binding layer 119 between the plates 16, 17, in order to connect them to each other practically inseparable. For connecting the electrode 118 to the source of high voltage, according to FIG. 5 there is provided a connecting lug 120 consisting of a thin metal foil and which, prior to the bonding of the two plates 16, 17, is connected electrically conductively with one end to the layer 118 and with its other end allowed to protrude beyond one edge of the plate.

The second modified form of a structural element 215 shown in FIG. 7 is only distinguished from the described elements 15 in that the electrode 218 consists, instead of a metal foil, of a metallic netting or fabric. Instead of a connecting lug 20, some wires 220 of the netting 218 project beyond the dielectric plates 16, 17. In making the element 215, the netting 218 is embedded, just like the electrode 18, between two plastic foils and between the dielectric plates 16, 17.

The principal advantage of the described apparatus for producing ozone results from the plate-shaped elements 15, 115 or 215, which may be produced in any desired form and shape according to the particular use, and arranged side-by-side in any desired number. No special difficulties are encountered in giving the structural elements the required mechanical and thermal strength and in incorporating them afterwards in the apparatus. The described structural elements permit of operating the apparatus, if desired, also with air dried incompletely or not at all. Moreover, it is of special importance that the elements 15, 115 or 215 enable the construction of comparatively small apparatus, in which within a given space, a relatively large total surface of electrodes may be installed.

What we claim is:

1. Method of making an electrode unit for an apparatus for producing ozone by a silent electric discharge between a plurality of flat plate-shaped electrodes, consisting essentially of the following steps: assembling two films of transparent organic thermoplastic dielectric material between two transparent dielectric glass plates and a smaller layer of conductive metal, to serve as electrode, between said films, evacuating air from between films and plates and from between films and electrodes, converting said films into a plastically soft condition by heating the assembly while simultaneously pressing the assembly, and finally allowing the assembly to cool.

2. Method of making an electrode unit for an apparatus for producing ozone by a silent electric discharge between a plurality of flat plate-like electrodes, consisting essentially of the following steps: depositing an electrically conducting metal layer, serving as an electrode, onto one side of a first transparent dielectric glass plate, said electrode being smaller than said glass plate, assembling a film of transparent organic thermoplastic dielectric material between said electrode-coated side of said first glass plate and a second transparent dielectric glass plate, evacuating air from between film and plates and from between film and electrode, converting said film into a plastically soft condition by heating the assembly while simultaneously pressing the assembly, and finally allowing the assembly to cool.

3. Method as defined in claim 1, in which the two

films of transparent organic thermoplastic dielectric material are films of polyvinyl acetate.
